UNITED STATES PATENT OFFICE.

HARRY RATYCIA, OF NEW YORK, N. Y.

NOVELTY DEVICE.

1,203,781.

Specification of Letters Patent.

Patented Nov. 7, 1916.

Application filed July 24, 1915, Serial No. 41,801. Renewed September 19, 1916. Serial No. 121,068.

To all whom it may concern:

Be it known that I, HARRY RATYCIA, a citizen of the United States, and residing at New York, in the county of New York and State of New York, have invented certain new and useful Improvements in Novelty Devices, of which the following is a specification, such as will enable those skilled in the art to which it appertains to make and use the same.

10 This invention relates to novelty devices and particularly to devices of this class designed for use in braiding belts and similar articles, and more particularly in making what is known as knotted braid-work, and with this and other objects in view the invention consists in a device of the class specified, constructed as hereinafter described and claimed, and the object of which is to hold 15 the cords from which the braid-work is made in the operation of making such work.

20 The invention is fully disclosed in the following specification, of which the accompanying drawing forms a part, in which the 25 separate parts of my improvement are designated by suitable reference characters in each of the views, and in which:—

Figure 1 is a sectional side view of my improvement and showing the same connected 30 with a table; Fig. 2 a plan view but showing the first step in the process of knotting or braiding a belt; Fig. 3 a view similar to Fig. 1 but showing the next step in the use of the device; and, Fig. 4 a view similar to Figs. 2 35 and 3 and showing the third step in the use of the device.

In the drawing forming part of this specification, I have shown at *a* a table or other support and, in the practice of my invention, 40 I provide a braid-work holder *b* comprising a head plate *b*² provided with a backwardly directed supplemental plate *b*³ and having a downwardly directed member *b*⁴ to which is pivoted at *b*⁵ an arm *c* composed of an inner 45 part *c*² and an outer part *c*³ hinged to the part *c*² at *c*⁴, and the outer part *c*³ is provided with an upwardly directed extension *c*⁵, the top of which is provided with a 50 spring clamp device *c*⁶, and the arm member *c* where it is connected with the part *b*⁴ is provided with an upwardly directed extension, and the said part *b*⁴ and said extension are provided with registering apertures *b*⁶ through which may be passed a pin to hold 55 the arm *c* in a rigid position, and the part *c*² of the arm *c* is provided with a spring de-

vice *d* secured thereto at *d*² and bent to form a projection *d*³ which fits between the abutting ends of the parts *c*² and *c*³ of the arms *c* and is adapted to hold the arm member *c*³ in operative position as shown in Fig. 1, and said spring is also provided with a thumb and finger or handle piece *d*⁴ by which it may be manipulated.

The bottom of the part *b*⁴ is provided with a backwardly directed arm *b*⁷ through which is passed a screw *b*⁸ provided at its lower end with a handle *b*⁹ and at its upper end with a clamp plate *b*¹⁰, and this construction forms a clamp mechanism by which the device may be secured to the edge portion of the table or other support as shown in Fig. 1. The head plate *b*² is provided adjacent to its front edge with a longitudinal slot *e* which opens at one end as shown at *e*² and which forms a front finger *e*³, and said head plate is also provided back of the slot *e* with upwardly directed hook pins *f*, two of which are shown.

The device herein described and claimed 80 is intended for the purpose of holding the cords *g* from which the braid-work or the knotted braid-work is to be formed, and in making knotted braid-work the cords are divided into separate series *g*², *g*³, *g*⁴ and *g*⁵ as 85 shown in Figs. 2 and 3, and each series contains four cords, and the said separate series of cords are passed into the slot *e* as shown in Fig. 2.

After the separate series of cords have 90 been passed into the slot *e* the ends of said series below the head plate *b*² are knotted together as shown at *g*⁶ in Fig. 1 to prevent said cords from pulling upwardly through said slot and the cords of the separate series 95 above the head plate *b*² are knotted together as shown at *g*⁷, in the following manner. The two central cords *g*⁸ of a series are raised and slipped under the spring clamp *c*⁶ as shown in Fig. 1 in order to keep them taut and 100 facilitate the knotting operation after which the two outer cords are knotted over or around the two central cords, and in this operation the outer cord *g*⁹ is first passed over the central cords *g*⁸ and the other outer cord *g*¹⁰ is passed downwardly through a loop 105 formed by the outer cord *g*⁹ and then under the central cords and up over the outer cord *g*⁹. This completes one-half of the knot shown at *g*⁷ in Fig. 2, after 110 which the outer cord *g*¹⁰ is passed over the central cords and the outer cord *g*⁹ is

passed downwardly through a loop formed by the outer cord g^{10} under the central cords and up over the cord g^{10} , and this operation will complete the second half of the knot 5 shown at g^7 , or completes the knot.

Each of the series g^2 , g^3 , g^4 and g^5 are tied in a similar manner, after which the 10 separate series are knotted together by bringing the outer cord g^6 of one series and the outer cord g^{10} of another series together to form two central cords g^{11} , as shown in Fig. 3, and the next adjacent cord on either side of the cords g^{11} are knotted over or around the cords g^{11} in the same manner as 15 the outer cords g^6 and g^{10} are knotted over the central cords in the separate series as shown in Fig. 2, and this will produce the result shown in Fig. 3.

It will be seen on considering Fig. 3 that 20 the separate series g^2 , g^3 , g^4 and g^5 as shown in Fig. 2 are knotted or tied together by three knots g^{12} formed in the manner hereinbefore set out, and it will be understood that on the completion of the next knotting 25 step which will be practically the same as the first step shown in Fig. 2 there will again be four knots g^7 as shown in Fig. 4.

After a few knots of the belt have been braided, the cords or the braid-work is 30 detached from the finger e^3 and the said braid-work is passed back over the head plate b^2 as shown in Fig. 4, and connected with the hook pins f which are passed upwardly therethrough, and this operation may be 35 repeated as the work of braiding or knotting proceeds so as to keep the braiding operation close to the head plate b^2 . The ends of the cords under the braid-work holder where they are knotted together at g^6 may 40 be of any desired length as may also the ends of said cords above the braid-work holder, and after a predetermined amount or length of the belt has been knotted or braided, it may be turned around on the 45 braid-work holder and the end portions of the cord under the braid-work holder may be knotted or braided to continue the length of the belt. The braid-work holder b , with the form of construction shown, may be 50 compactly folded together and carried in a pocket or handbag and easily shipped through the mail, if desired, but my invention is not limited to the particular details of construction of said braid-work holder 55 herein shown and described, and various changes therein and modifications thereof may be made, within the scope of the appended claims, without departing from the spirit of my invention or sacrificing its ad- 60 vantages.

Although, I have shown and described the method of braiding or knotting a belt in this application and although said method is of my invention, the said method is not claimed herein, the claims in this case being 65 limited to the work-piece or braid-work holder.

Having fully described my invention, what I claim as new and desire to secure by Letters Patent, is:—

1. A braid-work holder, comprising a head plate adapted to be secured to a support, said head plate being provided in its front edge portion with a longitudinal slot which opens outwardly at one end and backwardly of said slot, with upwardly extending hook members.

2. A braid-work holder, comprising a head portion adapted to be secured to a support and having a forwardly directed 80 arm provided with an attaching member, said head portion being provided with a longitudinal slot which opens at one end and backwardly thereof with means for adjustably connecting a braid-work piece there- 85 with.

3. A braid-work holder comprising a head piece provided with means for securing it to a support, said head piece being provided at the front thereof with a transverse 90 finger and rearwardly of said finger with upwardly directed attaching members.

4. A braid-work holder comprising a head portion adapted to be secured to a support and provided at its front with a transverse 95 finger and rearwardly of said finger with upwardly directed attaching members, said head portion being also provided with a forwardly directed arm provided at its end with an upwardly directed member having 100 an attaching device at the top thereof.

5. A braid-work holder comprising a head portion adapted to be secured to a support and provided at its front with a transverse finger and rearwardly of said finger with 105 upwardly directed attaching members, said head portion being also provided with a forwardly directed arm provided at its end with an upwardly directed member having 110 an attaching device at the top thereof, and said arm being composed of separate hinged parts.

In testimony that I claim the foregoing as my invention I have signed my name in presence of the subscribing witnesses this 115 19th day of July, 1915.

HARRY RATYCIA.
